UNITED STATES PATENT OFFICE.

JOHN SUNDQVIST, OF GEORGETOWN, CONNECTICUT.

TOY.

1,091,171.

Specification of Letters Patent. Patented Mar. 24, 1914.

Application filed November 11, 1912. Serial No. 730,774.

To all whom it may concern:

Be it known that I, JOHN SUNDQVIST, a citizen of Finland, Russia, residing at Georgetown, in the county of Fairfield and State of Connecticut, have invented certain new and useful Improvements in Toys, of which the following is a specification.

This invention relates to improvements in toys and more particularly to a wheeled toy having a platform disposed upon the wheel axle and figures secured to the platform for frictional contact with said wheels whereby a rotary motion is imparted to said figures; a figure disposed upon a flexible support secured to the platform is also provided and is actuated by contact with the moving parts of the first mentioned figures.

A full description of the invention will be found in the following specification, its new features pointed out in the appended claims and one embodiment illustrated in the accompanying drawing which forms a part of the specification and in which—

Figure 1 is a front elevation of my toy. Fig. 2 is a plan.

Like reference characters indicate corresponding parts throughout.

1 is a platform disposed upon an axle 2 provided with wheels 3, 3 and to the platform a box 4 is secured in which is disposed a front wheel 5. Near either end of the platform 1 a vertical shaft 6 is carried whereon a rotary figure 7 is mounted and adapted for frictional contact with the wheels 3, 3 and by them actuated. Arms 8, 8 carrying flags 9, 9 are provided for each figure and further a hat 10 is provided through which the shaft 6 extends and terminated at its upper extremity 11 in a ball 40 through which a shaft 12 passes that carries wheels or disks 13 at either end adapted for frictional contact, and consequent rotation, with the hat 10 of either figure 7.

Strands of ribbon 14 carrying rattles or bells 15 are secured to the shaft 12 and

actuated by it as it rotates and are further actuated by occasional contact with the flags or symbols 9. Upon the platform 1 a spiral spring 16 is secured that serves as a support for a small figure 17 the upper end or head of which is disposed in the path of motion of the strands 14 and actuated by contact therewith.

The toy when drawn over the floor or over a table top by means of a cord fastened in the ring 18 secured to the box 4 is very life-like as the figures 7 rotate, the wheels 13 and shaft 12 rotate, the strands 15 whirl and the figure 17 moves in a swaying manner upon its pedestal.

What is claimed is:

1. In a toy, a wheeled platform, rotary figures in frictional contact with said wheels, a transverse wheeled shaft associated with and actuated by the rotary figures, a flexible member secured to and actuated by said wheeled shaft and a figure seated upon a flexible support carried by said platform in the path of motion of the said flexible member.

2. In a toy, a wheeled platform, rotary figures in frictional contact with said wheels, a transverse wheeled shaft associated with and actuated by said rotary figures, a flexible member secured to and actuated by said wheeled shaft, arms provided with symbols secured to said rotary figures for intermittent engagement with said flexible member and a figure seated upon a flexible support carried by said platform in the path of motion of the said flexible member.

In testimony that I claim the foregoing as my own I have hereto affixed my signature in the presence of two subscribing witnesses.

JOHN SUNDQVIST.

Witnesses:

FREDERICK S. STURGES,
RALPH S. GREGORY.
